COMBINED COAT AND TROUSER HANGER HAVING BENT WIRE CONNECTING MEMBER

Norman E. Brooke, 3232 Rittenhouse St. NW.,
Washington, D.C.

Filed July 18, 1961, Ser. No. 124,939
2 Claims. (Cl. 223—91)

This invention relates to improvements in garment supports and is directed to a new and novel coat and trouser hanger.

Many styles of hangers have been developed for suspending coats and trousers together which perform the desired function efficiently, but which nevertheless are designed with a lack of ingenuity and foresight which materially affects the value of the article from the economic point of view both of the manufacturer and the consumer. Such lack of ingenuity also affects the ease with which the hanger can be handled in use, even though, as above stated it may serve its purpose as a supporting device after the coat and trousers have been respectively hung thereon and secured thereto.

It is an object of the present invention, in view of the foregoing, to provide a new hanger device for a coat and trousers wherein the individual parts are fabricated and joined together in a novel and unique manner which is not only simple and easy to use or operate, but which may be produced and sold economically. It is another object of this invention to provide a hanger which not only has the foregoing advantages, but one in which the said advantages are to be attained to a great extent by reason of the fact that an important element of the device may be readily formed from a suitable gauge, spring metal wire and can be secured to other elements with a minimum of labor.

Another object of the invention is to provide a hanger of the character stated wherein a coat supporting bar and a pair of jaw members for gripping and suspending a pair of trousers, are coupled together by a unique type of spring unit formed in one piece from a suitable length of spring wire, in such a manner that it may be firmly fixed to the coat bar with a single fastener element and wherein the unit includes spring legs to which the jaw members are fixed, which legs are biased to separate the jaw members, and there being an easily manipulated means connecting the legs by which the jaws may be drawn together to grip an article therebetween.

The invention will be best understood from a consideration of the following detailed description taken in connection with the accompanying drawings wherein:

FIGURE 1 is a view in perspective of the combination hanger of the present invention.

FIGURE 2 is a transverse section taken substantially on the line 2—2 of FIGURE 1.

FIGURE 3 is a view in perspective of the spring unit per se.

FIGURE 4 is a section detail taken on the line 4—4 of FIGURE 1.

Referring now more particularly to the drawing it will be seen upon reference to FIGURE 1, that the hanger comprises a long, one piece, longitudinally arcuate bar 10, to which are attached the one piece spring unit 12 and the pair of jaw members forming the trouser cuff gripping means 14.

The bar 10 is formed, preferably by stamping, from an elongate single piece of material of suitable character, such as aluminum or steel, or a combination of the same, or other metals, or it may be formed by the molding of a suitable plastic such, for example, as Lucite.

The bar 10 is of a suitable width and thickness. As an example, and without intending to in any way limit the invention, it may be stated that the bar may be about

2

one or one and-a-half inches in width and have a thickness of from about three-thirty seconds to one-eighth inch.

The bar 10, in addition to being generally arcuate throughout its length, is formed with a short centrally located arcuate portion 20, which curves sharply downward at its ends, as at 22, and then merges into the relatively long and very slightly longitudinally curved, or very nearly straight, oppositely directed extension portions 24, and these terminate in the downturned tips 26.

The bar 10, in addition, is preferably slightly transversely bowed, or arcuate, the convex side being uppermost, as seen in FIGURE 2.

At the transverse center of the bar 10, a hole 28 is formed to receive the threaded lower end or shank of a hanger hook, generally designated 30, the threaded shank end of which is designated 34.

The spring unit 12 is formed of a single length of spring wire. As best seen in FIGURES 2 and 3, the wire is bent or shaped midway of its length to form a unique top or head portion, generally designated 36 and the two spring leg portions 38, the free ends or tips of the latter being flattened as at 40, for the purpose hereinafter set forth.

In the fabrication of the head 36, the wire is bent to form the eye 42, by making a single loop, or convolution.

Each end of the eye forming loop extends outwardly and downwardly at an angle from the plane of the eye, which is substantially horizontal when the hanger is suspended, and each of such eye ends joins, or continues into, an end of a single convolution spring coil or loop, 44, the other end of which continues downwardly into the outwardly bowed leg 38. These spring coils lie opposed in a common vertical plane, perpendicular to the horizontal and on opposite sides, of and perpendicular to a vertical plane passing through the radial center of the eye 42.

The cuff gripping means 14, comprises the two jaw members 45. Each of these jaw members is formed from a strip of flat resilient metal which is longitudinally arcuate through the major portion of its length. Each jaw member has a short flat terminal portion 46, at each end. These terminal portions of the jaw members come into parallel, flat engagement when the jaw members are pressed together to grip a garment therebetween. Also, the jaw members are disposed with their concave sides opposed, or facing one another. This arrangement provides ample space between the jaw members inwardly of the portions 46, for the seam portions of trouser cuffs.

Each jaw member has a portion midway between its ends, pressed out to form the outwardly projecting loop 47, on the convex side of the jaw. Each of the loops 47 has the flat end 40 of a spring leg disposed therethrough and the loop is pressed against the end 40. Also, the tip 55 of the flat end 40 is bent outwardly slightly, as shown at 48, which effectively eliminates any chance of the end of the leg pulling out of the loop.

Each of the flat ends 46 of one jaw member is pressed in from the outer side to form an inwardly projecting button as shown at 48. Each of the flat ends 46 of the other jaw member is pressed from the inside of the member to form on the inside a depression 49 in position to receive the adjacent button 48, when the jaw members are in closed position, thereby providing a means for firmly gripping a garment.

To further add to the firm, non-slipping action of the jaw members when closed together, the inner surface of each is covered by a suitable friction material 50, which may be sponge rubber, plastic, felt or other suitable material.

Surrounding the spring legs and coupling them together is the elongate slip ring 51. This ring, when forced down

on the spring legs 38, is of proper length to draw the legs toward one another sufficiently to press the flat end of the two jaw members firmly together. If the material between the jaw members is thick the spring legs will yield and also the resilient arcuate jaw members will flex so that a proper gripping action is obtained.

Also it will be seen that, in addition to the resilient tensioning of the spring legs 38, by the action of forcing the ring 51 down thereon, the spring coils 44 will be tensioned, and when the ring is slid up on the legs, the spring 10 coils will assist in quickly separating the jaw members.

In the assembling of the device, a nut 52 is threaded onto the hook shank and the threaded end of the shank, below the nut, is passed through the hole 28. The eye 42, of the head of the spring unit, is then slipped onto the end of the hook shank and positioned against the concave underside of the coat bar. A nut 53 is then threaded onto the shank and, when the spring unit is adjusted so that the legs 38 and the spring convolutions 44 lie in a plane perpendicular to the coat bar, the nut is then drawn up tightly against the underside of the eye to press the latter tightly against the bar. If desired a suitable lock washer, of known form, may be placed between the eye 42 and the nut 53.

From the foregoing it will be seen that the combined coat and trouser hanger of the present invention, is of relatively simple design and may be made light in weight but of strong and durable construction. Also the parts are easily formed and can be assembled and firmly joined together easily and quickly.

I claim:

1. In a combined coat and trouser hanger wherein there is an elongate, longitudinally arcuate coat supporting bar and a pair of elongate cooperating jaw members disposed longitudinally of the concave side of said bar; the combination with said bar and jaw members of a one piece, substantially U-shaped inverted spring metal connecting member between the bar and said jaw members, said connecting member being formed from a single length of resilient wire and having spaced leg portions joined to a head portion, said head portion including a central eye part and a pair of spring parts connecting the eye part to the leg portions, means passing through the eye part and securing the latter to the underside of the bar midway between the ends of the latter, a suspension hook attached to the top of the bar midway between the ends of the bar, said leg portions having the ends thereof remote from said spring parts each secured to one of said jaw members midway of the ends thereof, said leg portions being biased to move apart and separate the jaw members, means connecting the leg portions for facilitating drawing together the ends thereof and the jaw members, each of said spring parts consisting of a single convolution of the wire, one end of each convolution

5

merging with a leg part, said eye part also consisting of a single convolution having two ends each of which merges with another end of a spring convolution and said spring convolutions being in edge to edge relation and lying in a plane perpendicular to the bar and said eye part lying in a plane which is substantially horizontal in the operative position of the hanger and perpendicular to the first plane, and said suspension hook having a shank end which passes through the bar and constitutes the said means passing through the eye and secured thereto.

2. A garment hanger comprising an elongate, longitudinally arcuate coat supporting bar having an aperture therethrough midway of its ends, a suspension hook including a shank having an end passing through said aperture from the convex side of said bar, a pair of elongate, longitudinally arcuate jaw members having their concave sides opposed, an inverted substantially U-shaped wire connecting member between said bar and said jaws and having a head portion and elongate longitudinally bowed spring leg portions, said head portion consisting of a loop forming an eye having two ends, each of said eye ends joining an end of a single convolution coil spring, the other end of each coil spring joining a top end of a spring leg portion, said coil springs being in edge opposed relation with their axes substantially parallel and extending longitudinally of said bar, said eye loop having its axis substantially perpendicular to and passing substantially centrally between said axes of said coil springs, said eye loop being disposed against the concave underside of said coat bar and having said hook shank passing therethrough, means securing said shank, eye loop and coat bar together with said spring leg portions bowing outwardly and being biased to separate at their free ends, means securing said free ends of the spring leg portions to said jaw members, and means connecting said leg portions and movable thereon for drawing the same and the jaw members together.
